(57) **CLAIM**

The ornamental design for a refrigerator drawer, as shown and described.

DESCRIPTION

FIG. 1 is a first perspective view of a refrigerator drawer showing my new design;

FIG. 2 is a top view thereof;

FIG. 3 is a front view thereof;

FIG. 4 is a left side view thereof;

FIG. 5 is a back view thereof;

FIG. 6 is a right side view thereof;

FIG. 7 is a bottom view thereof; and

FIG. 8 is a perspective view of a second embodiment of the refrigerator drawer;

FIG. 9 is a perspective view of a third embodiment of the refrigerator drawer; and,

FIG. 10 is a perspective view of a forth embodiment of the refrigerator drawer.

Drawings are shaded in FIG. 7 to indicate contrasting surfaces.
